UNITED STATES PATENT OFFICE

166,781

SPECTACLE FRAME ORNAMENT OR SIMILAR ARTICLE

Harry Weissman, New Hyde Park, N. Y.

Application March 22, 1952, Serial No. 19,005

Term of patent 14 years

(Cl. D57—1)

To all whom it may concern:

Be it known that I, Harry Weissman, a citizen of the United States and resident of New Hyde Park, in the county of Nassau and State of New York, have invented a new, original, and ornamental Design for a Spectacle Frame Ornament or Similar Article, of which the following is a specification, reference being had to the accompanying drawing, forming part hereof.

Fig. 1 is a front elevational view of a spectacle frame ornament, showing my new design.

Fig. 2 is a top plan view thereof.

Fig. 3 is a side elevational view thereof.

The dominant features of the design reside in the portions shown in full lines.

I claim:

The ornamental design for a spectacle frame ornament or similar article, substantially as shown and described.

HARRY WEISSMAN.
